HISTOLOGIC PROCESSING MACHINE

Jack Isreeli, Tuckahoe, N. Y., assignor to Technicon International, Ltd., Chauncey, N. Y., a corporation of New York

Application December 22, 1955, Serial No. 39,434

Term of patent 14 years

(Cl. D83—1)

FIG. 2

FIG. 1

FIG. 3

Fig. 1 is a perspective view of a histologic processing machine showing my new design;

Fig. 2 is a top plan view thereof on a smaller scale;

Fig. 3 is a side view thereof, in elevation, on a smaller scale, as viewed at the opposite side of the machine from that shown in Fig. 1.

I claim:

The ornamental design for a histologic processing machine, substantially as shown.
